United States Patent Office

Des. 191,997
Patented Dec. 26, 1961

191,997

TYPEWRITER

David O. Chase, Camillus, and Philip H. Stevens, Syracuse, N.Y., assignors to Smith-Corona Marchant Inc., Syracuse, N.Y., a corporation of New York

Filed Mar. 20, 1961, Ser. No. 64,375

Term of patent 14 years

(Cl. D64—11)

Des. 191,997

PAGE 2

FIGURE 1 is a front perspective view of a typewriter showing our new design;

FIGURE 2 is a front elevational view; and

FIGURE 3 is a top plan view thereof.

The dominant features of our design are shown in full lines.

We claim:

The ornamental design for a typewriter, substantially as shown and described.
